US0D1108209S

(12) **United States Design Patent** (10) Patent No.: **US D1,108,209 S**
(45) Date of Patent: ** Jan. 6, 2026

(54) **LID FOR FOOD STORAGE CONTAINERS**

(71) Applicant: **DELI GROUP CO. LTD**, Ningbo (CN)

(72) Inventor: **Wan Zheng**, Zhejiang (CN)

(**) Term: **15 Years**

(21) Appl. No.: **35/522,751**

(22) Filed: **Aug. 22, 2024**

(80) **Hague Agreement Data**

Int. Filing Date: **Aug. 22, 2024**

Int. Reg. No.: **DM/241183**

Int. Reg. Date: **Aug. 22, 2024**

Int. Reg. Pub. Date: **Oct. 25, 2024**

(30) **Foreign Application Priority Data**

Jun. 7, 2024 (CN) 202430351800.2

(51) **LOC (15) Cl.** **07-02**

Primary Examiner — Ricky Pham

(57) **CLAIM**

The ornamental design for a lid for food storage containers as shown and described.

DESCRIPTION

1.Lid for food storage containers

1.1:Front

1.2:Back

1.3:Left

1.4:Right

1.5:Top

1.6:Bottom

1.7:Perspective

The broken line disclosure in the drawings depicts environmental subject matter forming no part of the claimed design.
